MAGNETOSTRICTIVE PHONOGRAPH
PICKUP UNITStanley R. Rich, Cambridge, Mass., assignor to
Tobe Deutschmann, Canton, Mass.

Application May 15, 1946, Serial No. 669,777

5 Claims. (Cl. 179—100.41)

1

The present invention relates to a pickup device in which mechanical vibrations may be converted into sound energy. The present invention is more particularly applicable to phonograph pickup devices or to phonograph recording in which the operating element employs a wire having magnetostrictive properties maintained normally under torsional stresses.

The invention is an improvement over my co-pending application Serial No. 624,362, filed October 25, 1945, now U. S. Patent No. 2,471,542, granted May 31, 1949, and my application No. 652,926 filed March 18, 1946, now Patent No. 2,484,960, granted October 18, 1949.

The present application relates to means and method of construction of the phonograph pickup described in the aforementioned applications and is an improvement over the prior device in sturdiness of construction, reliability of operation, economy of manufacture and ease of assembly. The invention will be more fully described and its merits and advantages understood from the description in the specification below when taken in connection with the drawings illustrating an embodiment of the invention in which

Figure 1 shows a plan view of the unit with a portion of the casing broken away.

Figure 2 shows a section on the line 2—2 of Figure 1.

Figure 3 shows a detail of the magnetostrictive wire unstrained in torsion before assembled in the unit, and

Figure 4 shows the wire as assembled in the unit in its strained position but without magnet and case.

The device indicated in the figures is contained in a case 1 of insulating material which is recessed to receive the rest of the pickup unit. The case itself may be moulded of thermosetting resins, hard rubber or other material and while rectangular in shape, may be formed with inner projections 3, 4 and 5 to receive the semi-circular or horseshoe permanent magnet 6. This magnet 6 is preferably made of powdered material such as of the alloy of aluminum, nickel and copper which has high magnetic retentivity. Such magnetic powdered materials may be moulded in plastic to form a permanent magnet which has very high retentivity although somewhat higher reluctance than the magnet of the same solid alloy metal. The magnet 6 may be retained within the casing by means of the leaf spring 7 which may be positioned on the inside circular sector of the magnet and bear against one side 8 of the case or in any other suitable known manner.

2

As indicated in Figures 1 and 2, there is moulded in the side-surfaces of the magnet two slots or grooves 9 and 10 preferably aligned with one another in which slots the magnetostrictive wire 11 is placed. This magnetostrictive wire, which may be made of nickel or other suitable materials showing proper magnetostrictive properties, is originally formed as indicated in Figure 3 with loops 12 and 13 at either end bent around in different angular directions. In Figure 3 these planes coincide at 180°. The direction, however, may be less, if desired.

At the center of the wire 11 a small tube 12' is crimped over the wire. This may be soldered, welded or even pressed on. The tube 12' is short and of sufficient inner diameter to receive the stylus wire 14 which may be made of platinum or have a platinum iridium point 15 to give it extreme hardness.

20 The wire 14 is bent at an angle to provide a portion 16 parallel to the wire 11 and another portion 17 perpendicular to it. The wire 14 may be soldered, crimped or held in any suitable manner in the tube 12'. The wire 14 is originally straight 25 when the magnetostrictive wire is assembled in the case 1. After assembly in the case the wire is bent as described above. However, if desired the wire assembly may be completely finished before placing in the case by cutting a slot in the 30 case bottom a little greater than the length of the wire portion 16 to permit the stylus to be put through the case. The coil 18 is wound over the wire before being inserted in the case. This is accomplished by laying the coil 18 around the 35 tube 12' and then twisting the magnetostrictive wire forming the winding or coil 18 simultaneously on both sides of the tube 12'. It will be seen that in this way current flowing through the two halves of the coil 18 will be in opposite directions.

40 After a single layer of coil has been wound on the magnetostrictive wire, the magnetostrictive wire is dipped in latex or latex is painted or applied on the magnetostrictive wire where the coil is being formed, as shown at 30, Figure 4. If 45 desired, the wire may be coated with latex where the coil is to be formed before the coil is formed on the magnetostrictive wire. This serves both for damping and to secure the coil to the wire. When the coil has been wound on the magnetostrictive wire, the whole assembly is put in the 50 case. For this purpose the case is provided with a small hole or opening 19 or slot as mentioned above through which the wire 14 will project. The loops 12 and 13 are twisted to engage the slots 10 55 and 9 respectively thereby giving the desired tor-

sional stress to the magnetostrictive wire. The stylus wire may be formed with two bends 16, 17 terminating in the stylus point 15.

A guard 21 may be moulded as a part of the case around the position occupied by the stylus portions 16 and 17. This guard 21 may be wedge-shape with the highest wall portion 22 just short of the extension of the stylus point 15. In this way the pressure on the stylus will only permit it to be retracted below the surface of the highest point of the wedge of the guard.

When the magnet, coil and wire have been put in place, a cover 23 may be applied in which suitable terminal connections may be placed to connect to the ends of the coil 18.

When the stylus has been worn through ordinary playing, the case is opened and the assembly of the magnetostrictive wire coil and stylus is removed and a new one replaced. It will be found that the cost of replacement is extremely reasonable and quickly accomplished. The operation of the unit is the same as described in the co-pending applications, the torsional oscillation of the wire serving to increase and decrease the magnetic properties of the wire in such a way to vary the flux threading the coil to produce additive effects in both halves of the coil 18. This in part is responsible for the efficiency in operation of the present invention.

Having now described my invention, I claim:

1. A pickup device comprising a magnet having poles at opposite ends, said poles having slots across their faces near their ends, a magnetostrictive wire having return bends at each end adapted when twisted torsionally with respect to its length to engage said slots, means coating said magnetostrictive wire providing a flexible, yielding coating therefor, a stylus attached substantially at the mid-point of said magnetostrictive wire and a coil surrounding said wire positioned over said coating, said wire at each side of said stylus wound in opposite sense.

2. A pickup device comprising a magnet having poles at opposite ends, said poles having slots across their faces near their ends, a magnetostrictive wire having return bends at each end adapted when twisted torsionally with respect to its length to position the ends to engage said slots and be firmly held therein, a short tube attached substantially at the mid-point of said magnetostrictive wire, a stylus wire having one end engaging the open end of said tube and held thereby, and a coil surrounding said magnetostrictive wire at each side of said stylus wound in opposite sense.

3. A pick up device comprising a magnet having poles at opposite ends, said poles having slots across their faces near their ends, a magnetostrictive wire having return bends at each end adapted when twisted torsionally with respect to its length

to position the ends to engage said slots and be held firmly therein, a short tube attached substantially at the mid-point of said magnetostrictive wire, a stylus wire having one end engaging the open end of said tube and held thereby, said stylus wire being bent with two angular bends having a longer bend substantially parallel to the magnetostrictive wire and a coil surrounding said magnetostrictive wire at each side of said stylus wound in opposite sense.

4. A pick-up device for a phonograph and the like, comprising an insulating casing, a flat, arched magnet having poles at opposite ends of the arch, positioned in said casing, said ends having slots recessed in the side faces thereof aligned longitudinally of the magnet, a magnetostrictive wire having substantially the same diameter as the width of the slot with return bends at each end thereof parallel to the wire but normally not aligned with each other, said wire adapted when twisted torsionally with respect to its longitudinal axis to align said return bends to engage said slots whereby the wire is held in torsion, a stylus attached substantially at the mid-point of said magnetostrictive wire, a coil surrounding said wire at each side of said stylus wound in opposite sense, said stylus projecting externally of said casing.

5. A pick-up device comprising a magnet having poles at opposite ends, said poles having slots recessed in their faces near their ends, a magnetostrictive wire having substantially the same diameter as the width of the slot with return bends at each end adapted to be twisted torsionally with respect to its length to position the ends to engage said slots and be held firmly therein, a stylus attached substantially at the mid-point of said magnetostrictive wire and a coil surrounding said wire at each side of said stylus wound in opposite sense.
